H. H. MERCER
DRILLING APPARATUS

Filed July 26, 1927

UNITED STATES PATENT OFFICE.

HENRY H. MERCER, OF CLAREMONT, NEW HAMPSHIRE, ASSIGNOR TO SULLIVAN MACHINERY COMPANY, A CORPORATION OF MASSACHUSETTS.

DRILLING APPARATUS.

Application filed July 26, 1927. Serial No. 203,599.

My invention relates to drilling apparatus and particularly to a combined drill steel actuating and cleansing fluid pumping means.

5 It has for an object to provide improved drilling apparatus particularly adapted for drilling large holes of relatively great depth. Another object is to provide improved steel reciprocating and cleansing fluid pumping 10 means for the type of drilling apparatus disclosed in my copending application Ser. No. 742,337, filed October 8, 1924, to allow the same to handle greater lengths of drill rods and to drill deeper holes. A further object 15 is to produce a more effective pumping action whereby cleansing fluid at a higher pressure is available for cleansing the hole. Other objects and advantages will, however, hereinafter more fully appear.

20 In the accompanying drawings I have shown for purposes of illustration one form which my invention may assume in practice.

In these drawings,—

Fig. 1 is an elevation view of a portion of a drilling apparatus with my improved steel reciprocating and cleansing fluid pumping means associated therewith, parts being broken away to facilitate illustration.

Fig. 2 is a central vertical section through 30 my improved steel reciprocating and fluid pumping device on the line 2—2 of Fig. 1.

In this illustrative embodiment of my invention I have shown a part of the frame of the drilling machine designated as 1 upon 35 which vertical supporting and guiding standards 2 are secured in the manner described in my copending application above identified. The drill steel actuating mechanism is carried in a frame including upper 40 and lower head members 3 and 4 slidably mounted upon the vertical supporting standards 2 by means of bearing and guiding portions 5 in the head members. These upper and lower head members are secured together by means of vertical rods 6 and suitable retaining means such as nuts 7.

For the purpose of actuating the drill steel a crank shaft 8 is mounted in the upper head member 3 and driven from a suitable source of power by mechanism fully described in my above identified application. This crank shaft has a plurality of cranks which impart reciprocatory motion through the connecting rods 9 to the combined steel 55 reciprocating and fluid pumping means gen-

erally designated 10 and this mechanism in turn imparts reciprocatory movement to the drill chuck 11 which carries the drill rods 12.

The steel reciprocating and fluid pumping means comprises a plurality of concentric cylinders, the lower inner and outer cylinders being designated 14 and 13, respectively, and the upper cylinders designated 15, 16 and 17. These cylinders are closed at their ends by upper and lower cylinder heads 18 and 19, respectively, and by means of an intermediate head 20 common to the upper and lower sets of cylinders. A supplemental upper head 21 is mounted adjacent the head 19 for the purpose of providing a compressed fluid receiving chamber 22. All of these head members and cylinders are secured together by a plurality of longitudinal bolts 23, which extend through the head members between the outer and inner cylinder members. A piston 24 reciprocates within the lower cylinder 14 and a second piston 25 reciprocates within the upper cylinder 17, both of these pistons being secured to a common piston rod 26 secured at its lower end to the chuck member 11. Stub shafts 27 project outwardly from the intermediate head at diametrically opposite points and to these shafts are connected the rod bearings 28. Also formed integral with each of these stub shafts are guiding members 29, shown in Fig. 1. Each of these guide members is provided with a semi-cylindrical recess 30 adapted to be slidably guided upon guiding sleeves 31 surrounding each of the retaining rods 6, and loosely mounted thereon so that they may be rotated relative to the shaft 6 at frequent intervals to prevent excessive wear upon only one side.

Inlet ports 32 in the lower cylinder head member controlled by valves 33 serve to admit air to the lower end of the lower cylinder. The inlet means for the upper end of this cylinder comprise passages 34 leading into a hollow portion of the intermediate head 20 through the stub shafts 27, inlet ports 35 and valves 36. The hollow chamber 37 in the intermediate head serves as a storage chamber and tends to equalize the flow of air through the passages 34. Air is discharged from the lower cylinder through discharge ports 38 controlled by valves 39 and is conducted by way of the annular space between the cylinders 13 and 14.

14 through passages 40 in the intermediate cylinder head into the annular space between the upper cylinders 15 and 16, by way of passages 41 controlled by valves 42, 6 to the lower end of the upper or high pressure cylinder 17, and into the upper end of this same cylinder through passages 43 controlled by valves 44. Air is discharged from the upper and lower ends of the high pressure cylinder through ports 45 controlled by valves 45^a into the annular space between the cylinders 16 and 17 through the passages 46 into the receiver chamber 22.

Suitable means are provided for regulating the discharge of air from the chamber 22 which comprises an outer sleeve member 47 provided with slots 48 threaded into the head member 21, and an inner sleeve 49 provided with slots 50 which are adapted to 20 register with the slots 48, this inner sleeve member being secured to a cap 51 by means of a stud bolt 52. The cap member 51 is threaded on the end of the outer sleeve member and may be clamped thereto by means 25 of a clamping device 53. It will be noted that upon loosening the clamping device 53 and stud bolt 52 the sleeves may be adjusted relative to one another to control the extent of the opening between the receiver chamber 22 and the interior of the inner sleeve.

It will be observed that the piston rod 26 is hollow throughout its entire length and terminates at its upper end within the interior of the inner sleeve 49. A casing 54 is secured to the upper and lower head members 3 and 4, respectively, which encloses the entire mechanism and prevents the entrance of abrasive material.

In operation, the connecting rods 9 will 40 be positively reciprocated by the crank shaft 8, this motion being transmitted directly to the intermediate head 20 and all of the cylinder elements. The pistons and piston rod, being free to move relative to the cylinder members, will tend to move in a downward direction when the cylinder is being lifted and thus the upward movement of the drill chuck will be somewhat later than the movement of the connecting rods. Also 45 when the downward movement of the drill chuck is resisted by an outside force as when the drill bit delivers a blow, the cylinder elements will move downward relative to the pistons and piston rod. This action will 50 continuously pump air through the ports 32 and 35 into the lower cylinder where it will be compressed a certain amount, the same being discharged into the upper cylinder through passages 41 and 43 where it will be 55 compressed to a considerably higher pressure, and discharged into the receiver chamber 22. This compressing action will apply a yielding resistance to the relative movement between the cylinder and piston 60 elements and it will be observed that the

discharge ports are spaced at a distance from the ends of the cylinders so that when the piston overruns these ports a certain amount of air will be trapped to serve as a pneumatic cushion, thus insuring against the 70 possibility of the piston striking against the cylinder heads. This pneumatic connection between the positively driven element and the drill bit is very essential in order to produce an effective blow. At the same time 75 compressed fluid is admitted from the chamber 22 into the hollow piston rod through the hollow drill rods, escaping through the drill bit and lower end of the hole whereby the hole is effectively cleansed of all cuttings. The amount of cushioning action may be varied to suit different operating conditions by adjusting the size of opening through sleeves 47 and 49, thus regulating the discharge pressure for the high pressure 80 cylinder.

As a result of compounding the pumping cylinders, it will be clear that the working pressure in the upper cylinder is considerably increased, thereby effecting a corresponding 85 increase in the pneumatic resistance to relative movement of the cylinder and piston elements, which will enable the machine to successfully operate with a greater length of drill rods and at the same time provide the 90 desired flexibility between the positive drive element and drill chuck. Also by reason of this compound action cleansing fluid is available at considerably higher pressures so that the cuttings from a deep hole may be more 95 effectively removed.

While I have in this application specifically described one form which my invention may assume in practice, it will be understood that this form of the same is shown for purposes of illustration and that the invention may be modified and embodied in various other forms without departing from its spirit or the scope of the appended 105 claims.

What I claim as new and desire to secure by Letters Patent is:

1. A rock drilling apparatus comprising a power reciprocated member, a drill steel actuated thereby, means for providing a 115 pneumatic connection between said member and said steel comprising a plurality of cylinders and pistons cooperating therewith, and fluid conducting and valve means associated with said cylinders and pistons whereby they act as a compound fluid compressor pump.

2. A rock drilling apparatus comprising a power reciprocated member, a drill steel actuated thereby, means for providing a 125 pneumatic connection between said member and said steel comprising a plurality of cylinders and pistons cooperating therewith, fluid conducting and valve means associated with said cylinders and pistons whereby 130

they act as a compound fluid compressor pump, and means for conducting fluid discharged from said pump to a bore in the drill steel.

5 3. A rock drilling apparatus comprising a power reciprocated member, a drill steel actuated thereby, means for providing a pneumatic connection between said member and said steel comprising a plurality of cylinders and pistons cooperating therewith, fluid conducting and valve means associated with said cylinders and pistons whereby they act as a compound fluid compressor pump, and means for controlling the discharge pressure of said pump.

10 4. A rock drilling apparatus comprising a power reciprocated member, a drill steel actuated thereby, means for providing a pneumatic connection between said member and said steel comprising a plurality of cylinders and pistons cooperating therewith, and means for conducting fluid discharge from one cylinder into another cylinder whereby said second cylinder and piston are subjected to higher working pressures.

15 5. A rock drilling apparatus comprising a power reciprocated member, a drill steel actuated thereby, means for providing a pneumatic connection between said member and said steel comprising a plurality of cylinders and pistons cooperating therewith, means for conducting fluid discharge from one cylinder into another cylinder whereby said second cylinder and piston are subjected to higher working pressures, and means for conducting pressure fluid from said second cylinder to a bore in the drill steel for cleansing the hole.

20 6. A rock drilling apparatus comprising a power reciprocated member, a drill steel actuated thereby, means for providing a pneu-

matic connection between said member and said steel comprising a plurality of cylinders and pistons cooperating therewith, and fluid conducting and valve means associated with said cylinders and pistons whereby they act as a compound fluid compressor pump, each of said pump cylinders being double acting.

25 7. A rock drilling apparatus comprising a power reciprocated member, a drill steel actuated thereby, and means for providing a pneumatic connection between said member and said steel comprising a plurality of cylinder and piston pumping elements connected in tandem compound relation.

30 8. A rock drilling apparatus comprising a power reciprocated member, a drill steel actuated thereby, means for providing a pneumatic connection between said member and said steel comprising a plurality of cylinders mounted in tandem and movable with said member, pistons cooperating with said cylinders and movable with the drill steel, and fluid pressure means acting on said pistons, the pressure acting on one piston being higher than the pressure acting on another.

35 9. In a drilling apparatus, combined steel reciprocating and cleansing fluid pumping means comprising a positively reciprocated member, a drill steel actuated thereby, and means for providing a yielding connection between said member and said steel comprising a plurality of cylinders and pistons cooperating therewith, said cylinders and pistons constituting double acting pumping elements on relative movement of said member and said steel, the air supplied to one of said cylinders being higher than atmospheric pressure.

In testimony whereof I affix my signature.

HENRY H. MERCER.
